[57] **CLAIM**

The ornamental design for a caddy for tableware utensils or similar articles, substantially as shown and described.

DESCRIPTION

FIG. 1 is a front elevation view of a caddy for tableware utensils or similar articles showing our design. FIG. 2 is an elevation of one end thereof.

FIG. 3 is a top plan view thereof.

FIG. 4 is a vertical sectional view thereof, as seen on the line 4—4 of FIG. 3.

The opposite end of the caddy for tableware utensils or similar articles is the same as FIG. 2 in reverse. The rear elevation is the same as FIG. 1.

The bottom plan view is plain and the same as FIG. 3 is outline.

Fig. 2.

Fig. 1.

Fig. 3.

Fig. 4.
